CHAIR AND TABLET ARM ASSEMBLY

John H. Clarin, Oak Park, Ill., assignor to Clarin
Mfg. Co., Chicago, Ill., a corporation of Illi-
nois

Application June 12, 1952, Serial No. 293,048

11 Claims. (Cl. 155—128)

1

This invention relates to chairs having tablet arms attached thereto and is more particularly concerned with a folding chair having a collapsible tablet or writing arm mounted thereon in a manner such that it may be readily extended to a horizontal writing position forward of and above the seat, moved to a vertical position at one side of the chair so as not to obstruct the seat, or collapsed to a storage position against the flat side of the folded chair.

For many years the provision of tablet arms on chairs has been an acknowledged solution to the problem of providing writing space, wherever permanently installed desks or tables are not practical. Most of the previously known tablet-arm type chairs, however, were so designed that the tablet-arm was held in fixed relation to the seat and, consequently, made it very difficult for a person to seat himself or to rise from the chair. Even in those chairs which could be folded and the tablet arm collapsed, it was generally necessary to fold the chair in order to collapse the tablet arm. This dependent movement of the chair and arm, of course, detracts considerably from the utility of the chair in a class room or the like, where the chairs are necessarily grouped in close relation to one another and it is important that the student be able to seat himself or rise from the chair without being obstructed by the tablet arm and without having to fold the chair. Furthermore, the previously used collapsible tablet arms were generally unstable and often very difficult to move into and out of writing position. A previous solution to the above discussed problems has been presented in my co-pending application, Serial No. 242,248, filed August 17, 1951, and the present application is directed to an improved form of the chair disclosed therein.

The main object of the present invention is to provide a chair having a tablet arm which may be extended over the seat for writing or other purposes, and moved to an inoperative position at one side of the chair so as not to obstruct the seat; to provide a tablet arm assembly which is associated with a folding chair in a manner affording relative movement between the tablet arm and chair so that the tablet arm can be moved into and out of its operative position and, also, so that the entire chair and tablet arm assembly may be compactly collapsed for storing; to provide a folding chair and collapsible tablet arm assembly having a sturdy overall construction of high rigidity and affording independent collapsing and extending of the chair and tablet

arm, respectively; and to provide a simple collapsible tablet arm assembly for folding chairs which may be easily and economically manufactured and which may be quickly and easily moved into and out of its various positions for use or storage.

An illustrative embodiment of this invention is shown in the accompanying drawings, wherein:

Figure 1 is a perspective view of a folding chair 10 and tablet arm assembly to which this invention is applied, the tablet arm being shown in its inoperative lowered position at one side of the chair.

Figure 2 is a side elevational view of the chair 15 and tablet arm assembly fully collapsed for storage.

Figure 3 is an enlarged fragmentary top elevational view of the chair and tablet arm assembly, with the tablet arm extended but raised to 20 a vertical position so as not to obstruct the seat.

Figure 4 is a side elevational view of the chair and tablet arm assembly with the tablet arm in its horizontal, operative position above the chair seat.

25 Figure 5 is an enlarged sectional view taken on the line 5—5 of Figure 4.

A folding chair 6 embodying certain of the novel features of the present invention is illustrated in the drawings. Although the present invention is adapted also for use with chairs 30 having their legs permanently fixed in position relative to the remainder of the chair, it is particularly suitable for use with the folding type chair and will, therefore, be described in connection with the latter.

35 As shown, the folding chair 6 includes a back rest 7 fixed to a U-shaped frame 8 providing at its lower extremities a pair of forward legs 9, a seat 10 and a pair of rearward legs 11 which are foldable relative to the U-shaped frame 8 in the manner described in my previously mentioned co-pending application, Serial No. 242,248, and a tablet arm assembly 12 constructed and arranged in accordance with this invention.

40 The back rest 7 is preferably of metal but may readily be made of wood or other suitable material and may include suitable padding material if desired. The U-shaped frame 8, as seen particularly in Figs. 1 and 2, is formed from a flat strip of metal with the edges being rolled to provide beads 13 on the outer surface of the frame. The beaded portions of the frame act as stiffening means for the frame and also provide a channel web for attaching a pair of cross-braces 45 14 and 15 in spaced relation between the forward

legs 9. These cross-braces are formed with rolled edges in the manner of the U-shaped frame 8 and are preferably secured to the latter by welding opposite flattened end portions of each of the cross-braces 14 and 15 in position on the frame 8 between the beads 13, with the braces disposed on respectively opposite sides of the U-shaped frame. The upper cross-brace 14 also serves to support the seat 10 in its operative position.

The seat 10 comprises a wood panel bound 10 at its edges by a channel shaped metal strip 16 but obviously may be readily made of other material or design. The seat 10 is supported on opposite sides adjacent its rear edge by a pair of links 17 which are pivotally connected at 16 their upper ends to an upper portion of the frame 8 and at their lower ends to the metal strip 16 around the seat. A lower extension 18 (Fig. 4) on each of the links 17 is adapted for engagement with the upper cross-brace 14 to limit the forward swinging movement of the links as the seat 10 is moved to its operative position. Furthermore, a stud 19 is provided on the metal strip 16 to the rear of each of the links 17 to limit the rearward movement of the links as the seat is moved rearwardly and upwardly to its collapsed position shown in Fig. 2. This latter mentioned coaction between studs 19 and the links 17 prevents the seat 10 from moving to an over-center position with respect to the U-shaped frame 8, from which position it would be difficult to disengage the seat and move it back to its chair-forming position.

Forwardly of the seat supporting links 17, the seat 10 is further pivotally supported at opposite sides thereof by the upper ends of a pair of strap members 20 which are pivotally connected at an intermediate point, by a pin 21, to the U-shaped frame 8. The lower ends of the strap members 20 are fixed to the upper ends of the rearwardly extending pair of legs 11 for movement therewith about the pivot center 21 on the frame 8. As in the case of the forwardly extending legs 9, a pair of brace members 22 are provided between the rearward legs 11. The end portions of each of the four legs are preferably provided 45 with a molded rubber foot 23 or the like.

It will be seen from the foregoing and by looking particularly at Fig. 4, that movement of the seat 10 relative to the U-shaped frame 8 will 50 carry with it the rearward pair of legs 11 to collapse and extend the seat and legs, as desired.

The tablet arm assembly 12 includes a conventional tablet arm 24, preferably of wood, which is secured in movable relation to one side of the chair 6 by a bracket 25 fixed to an upper portion of the U-shaped frame 8, as by rivets, and a post 26 which is pivotally connected at its lower end by a pin 27 or the like to a lower portion of the chair frame. The post 26 is preferably a metal angle member and is braced against movement laterally of the chair by a cross-brace 28 which is fixed at one end to the lower end of the post and extends across to the opposite side of the U-shaped frame 8, where it has an inwardly turned end portion 28.1 pivotally fixed in position on the inner face of the frame. An angle brace 29 between post 26 and the transverse brace 28 adds further rigidity to the post.

The upper end of post 26 has a flange extension 30 bent horizontally to provide a bearing surface for the tablet arm at the upper end of the post, as seen best in Fig. 5. A short angle member 31 is also secured, as by rivets, to one flange of the post 26 to form therewith a chain-

nel section immediately underlying the horizontal bearing surface 30. Opposite sides of this channel section have axially aligned openings therethrough to receive a transverse hinge pin 32 which projects beyond the outer side of the post 26 in a direction away from the chair 6. A yoke member 33 is provided with aligned openings through its leg portions for pivotally mounting the yoke on the projecting end portion of pin 32, with its bight spaced outwardly from the pin. A washer 34 is preferably placed between yoke 33 and the adjacent flange of post 26 to facilitate free turning movement of the yoke on the hinge pin 32 relative to the post. The structure just described provides a double pivot support for the forward end of the tablet arm in a manner to be described.

As previously indicated, the support for the rearward end of the tablet arm is provided by the bracket 25 which is fixed to the upper portion of the U-shaped frame 8. An intermediate portion of the bracket 25 has fixed thereto one end of a strap member 36 (Fig. 1) which extends angularly away from the bracket 25 and terminates at its upper end in a generally vertical section spaced from the upper end of the bracket 25. A yoke member 37 is secured, as by welding, to the spaced upper ends of strap 36 and bracket 25 to provide a horizontal bearing surface at the top of these members. Aligned openings are formed in strap 36, yoke 37 and bracket 25 to provide a journal bearing for a transverse hinge pin 38. The outer end of the pin 38 has non-rotatably fixed thereto the bight portion of another yoke 39, which has aligned openings through its leg portions, and a cylindrical bearing member 40 is fixedly disposed between these openings to provide therewith an elongated cylindrical bearing surface. This cylindrical bearing 40 is positioned for horizontal alignment with the generally cylindrical bearing surface provided by the yoke member 33 on the post 26 at the forward end of the chair. Consequently, there is provided suitable means for rotatably supporting opposite ends of an elongated rod 41 which provides hinged movement between the tablet arm and its supporting elements.

The rod 41 is supported at its rearward end, on the underside of the tablet arm 24, by a depending flange portion of a channel bracket 42 which is secured to the tablet arm by screws or the like. An opening is provided in the depending portion of bracket 42 to receive the rod 41. The rod 41 extends through the cylindrical bearing 40 on the yoke 39 for sliding movement relative thereto and for rotation in the bearing. Further, the channel bracket 42 is of a width such that, when the rear flange of the channel abuts the yoke 39, it may be rotated about the axis of rod 41 to embrace the yoke 39 and also the inner yoke 37 between its flanges and thus prevent relative sliding movement between the rod 41 and its cylindrical bearing 40 so as to lock the tablet arm in its forward operative position as shown in Fig. 4.

The forward end of the tablet arm provides, with the yoke 33 on the forward post 26, means for receiving the forward end of rod 41 which comprises a yoke 43 secured to the underside of the tablet arm 24 and having aligned openings therethrough for receiving the rod. More specifically, an elongated channel member 44 is secured to the underside of the tablet arm 24 as shown in Fig. 1, and the yoke 43 is fixed, as by welding, to the end of channel 44 adjacent post

26. The yoke 43 is positioned astride the yoke 33 (Fig. 1) on the post 26 to provide therewith a bearing means for the forward end of the rod 41. The rod is preferably removably positioned in the various aligned openings described above in a manner preventing axial movement of the rod relative to the tablet arm. In the illustrated embodiment each end of the rod 41 includes a peripheral groove (not shown) for holding a spring clip or washer 45 (Fig. 3) to prevent axial movement of the rod.

It is seen, therefore, that the tablet arm is mounted for vertical swinging movement relative to the chair, through the horizontal hinged connection afforded by the rod 41. Further, it is evident that the horizontal pivots provided by hinge pins 32 and 38, the swinging movement provided for post 26, and the relative sliding movement afforded between rod 41 and its rear bearing support 40, permit the arm to move rearwardly and downwardly with respect to the chair to assume the position shown in Fig. 1. The collapsing of the chair 6 through movement of the seat 10, in the manner described above, will then permit the tablet arm to be folded toward the chair about the axis of rod 41 to achieve the storage position shown in Fig. 2. It will be noted that the bracket 25 includes an outwardly turned flange 46 which limits the rearward movement of the post 26 and insures alignment of the post with the side of U-shaped frame 8 when collapsed.

The collapsible chair and tablet arm assembly described above is economical to manufacture, simple to operate, and provides a rigid writing surface. The movement of the tablet arm and the chair to and from their various positions for use and storage is smooth and simple to achieve. The tablet arm assembly has four positions which contribute much to the utility of the structure. The horizontal, extended position of the arm (Fig. 4) provides a convenient writing surface which is firmly supported in position through the coaction of the post 26 with the channel 44 on the underside of the arm, and the coaction of the channel 42 with the yoke 37 at the rear of the arm which prevents any relative sliding movement between the arm and the chair. The extended vertical position of the arm (Fig. 3) provides an unobstructed path to the seat 10, with the tablet arm readily movable from such position to its horizontal writing position. The collapsed position of the arm alongside the chair (Fig. 1) provides for free use of the chair apart from its utility as a desk, and the collapsed position of the arm and chair (Fig. 2) provides for storage of the chair and tablet arm unit in a minimum of space.

It will also be noted that the tablet arm and the chair are independent of each other in their folding movements. Consequently, the chair may be conveniently used with the arm collapsed to an unobtrusive position at the side of the chair and, further, there can be no confusion as to what element to fold or extend first in moving the chair to its storage and operative positions, respectively. In folding the chair it is immaterial as to whether the chair or arm is folded first, apart from the obvious final step of folding the arm across the front of the collapsed chair. Similarly, in moving the chair and arm to their extended positions, once the arm has been swung away from its position overlapping the collapsed chair, it matters not whether the arm or the chair is first to be extended. Further, the absence of

connections between the seat and the collapsible tablet arm assembly and the spacing provided therebetween avoids the troublesome catching of clothing between these relatively movable parts, as is the case in some of the prior art constructions. It will also be readily apparent, from the construction of the illustrated embodiment, that it may be readily attached to existing chairs not having tablet arms.

Although but one specific embodiment of this invention has been herein shown and described, it will be understood that details of the construction shown may be altered without departing from the spirit of the invention as defined by the following claims.

I claim:

1. A collapsible tablet arm assembly for support on a chair comprising, a tablet arm, an elongated member fixed to the underside of said tablet arm, a pair of elements providing aligned journal bearings receiving said elongated member, each of said elements having a support member connected thereto for relative movement about an axis generally normal to the axis of said journal bearing, one of said elements affording relative axial sliding movement of said elongated member, and each of said support members including means for attachment to a chair in supported relation thereto.

2. A collapsible tablet arm assembly for support on a chair, comprising a tablet arm, a rod fixed to the underside of said tablet arm in generally longitudinally extending, spaced relation thereto, a pair of elements providing aligned journal bearings receiving said rod, one of said elements being arranged in axially fixed relation to said rod, the other of said elements slidably receiving said rod for relative axial movement therebetween, and a support member connected to each element of said pair for relative movement about an axis generally normal to the axis of said journal bearing, one of said support members including means providing for rigid attachment thereof to the chair, the other of said support members including means providing for pivotal attachment thereof to the chair at a point on said member beneath its connection with said journal bearing element, and a releasable lock means on said assembly for preventing said relative axial sliding movement between said rod and said other journal bearing.

3. A collapsible tablet arm assembly for support on a chair comprising, an elongated tablet arm, a rod fixed to the underside of said tablet arm in generally longitudinally extending, spaced relation thereto, a pair of elements providing aligned journal bearings receiving said rod, one of said elements being disposed at the forward end of said rod with its journal bearing fixed in axial relation to said rod, the other of said elements affording relative axial movement of said rod, an elongated member having one end connected to said one element for relative movement about an axis generally normal to the axis of said rod, the other end of said elongated member including means providing for pivotal connection with a forward portion of the chair, a supporting bracket connected to said other element for relative movement about an axis generally normal to the axis of said rod, said supporting bracket including means providing for a fixed connection with a rearward portion of the chair and including a part disposed in the path of movement of said one end of said elongated member, and a releasable locking means on said

assembly operable to prevent said axial sliding movement between said rod and said other element.

4. In combination with a chair, a collapsible tablet arm assembly comprising, a generally vertical supporting member fixed at its lower end to a forward portion of said chair for relative swinging movement through a generally vertical path along one side of said chair, a supporting bracket fixed to said chair rearwardly of said vertical supporting member, a tablet arm, means hingedly connecting longitudinally spaced portions of said tablet arm to said supporting member and bracket affording lateral tilting movement of said tablet arm relative to said chair, said connecting means also including a pair of elements affording relative movement between said tablet arm and said supporting bracket and supporting member, respectively, about a pair of axes generally normal to the hinge axis, one of said elements affording relative movement of said tablet arm along said hinge axis whereby said tablet arm may be moved in a path generally parallel to the path of said supporting member.

5. In combination with a chair, a collapsible tablet arm assembly comprising, a supporting member pivotally connected at one end to a forward portion of said chair for movement through a generally vertical path along one side of said chair, a supporting bracket fixed to said one side of said chair rearwardly of said supporting member, a tablet arm, means connecting said tablet arm to said supporting member and said supporting bracket comprising, an elongated member fixed to the underside of said tablet arm, a double pivot element interconnecting the upper end of said supporting member with one end of said elongated member for relative movement therebetween about a pair of generally normal axes, and additional means pivotally connected to said supporting bracket for slidably, rotatably receiving the other end portion of said elongated member.

6. In combination with a chair, a collapsible tablet arm assembly comprising, a supporting member pivotally connected at its lower end to a forward portion of said chair for movement relative thereto through a vertical path along one side of said chair, a supporting bracket fixed to said chair rearwardly of said supporting member and in general alignment therewith, a tablet arm, means connecting said tablet arm to said supporting member for movement relative thereto about a pair of generally normal axes whereby said tablet arm may be laterally tilted from a horizontal to a vertical position and may also be rotated relative to said supporting member in a plane parallel to said vertical path alongside said chair, and additional means pivotally connecting said tablet arm to said supporting bracket for sliding movement relative thereto to permit said lateral tilting movement of said tablet arm as well as said relative rotation of said supporting member and tablet arm alongside of said chair.

7. In combination with a chair, a collapsible tablet arm assembly comprising, a supporting member pivotally connected at one end to a forward portion of said chair for movement relative thereto through a generally vertical path along one side of said chair, a supporting bracket fixed to said chair rearwardly of said supporting member and in general alignment with the upper portion of the path of movement of said member, a tablet arm, means connecting said tablet

arm to said supporting member and to said supporting bracket, said connecting means including a rod fixed to the underside of said tablet arm and journaled in pivot elements mounted, respectively, on said supporting member and said supporting bracket, one of said pivot elements affording sliding movement between said rod and said one element.

8. In combination with a chair, a collapsible tablet arm assembly comprising, a supporting member pivotally connected at one end to a forward portion of said chair for movement relative thereto through a generally vertical path along one side of said chair, a supporting bracket fixed to said chair rearwardly of said supporting member and in general alignment therewith, a tablet arm, means connecting said tablet arm to said supporting member and to said supporting bracket, said connecting means including a rod fixed to the underside of said tablet arm, a pair of bearing elements pivotally mounted, respectively, on said supporting member and on said supporting bracket in position to receive spaced portions of said rod for rotation relative thereto, said rod being axially fixed with respect to one of said elements and being axially slidably relative to the other of said bearing elements.

9. In combination with a chair, a collapsible tablet arm assembly comprising, a supporting member pivotally connected at one end to a forward portion of said chair for movement relative thereto through a generally vertical path along one side of said chair, a supporting bracket fixed to said chair in general alignment with said supporting member and disposed in a rearward portion of the path of movement of the latter, a tablet arm, means connecting said tablet arm to said supporting member and bracket, said connecting means including a rod fixed to the underside of said tablet arm, a pair of bearing elements pivotally mounted, respectively, on said supporting member and said supporting bracket, one end portion of said rod being journaled in the one bearing element on said supporting member in axially fixed relation thereto, another portion of said rod being journaled in the other bearing element on said supporting bracket in axially slidable relation thereto, releasable locking means on said assembly for preventing said axial sliding movement of said rod relative to said other bearing element, and means on said supporting bracket limiting the extent of rearward movement of said supporting member.

10. In combination with a chair, a collapsible tablet arm assembly comprising, a supporting member pivotally connected at one end to a lower portion of one of the forward legs of said chair for swinging movement through a generally vertical path along one side of said chair, a supporting bracket fixed to said one side of said chair rearwardly of said connection for said supporting member, a tablet arm extending along said one side of said chair, means connecting said tablet arm to said supporting member and said supporting bracket comprising, an elongated member fixed to the underside of said tablet arm in position for connection with said supporting member and said supporting bracket, means on the upper, free end portion of said supporting member providing a connection with the adjacent end portion of said elongated member, said means including a double pivot element affording relative rotation between said tablet arm and said supporting member about the axis of said elongated member.

gated member and, also, about an axis normal to said elongated member whereby said tablet arm may swing about the upper end of said supporting member generally in the path of movement of the latter, means on said supporting bracket for connection with said elongated member including a yoke element mounted for pivotal movement about an axis normal to the longitudinal axis of said elongated member, said yoke element including aligned openings through its leg portions for slidably, rotatably receiving said elongated member, and additional means on said tablet arm assembly positionable to prevent said sliding movement of said elongated member relative to said yoke element.

11. In combination, a folding chair comprising pairs of front and rear legs and a seat portion hingedly interconnected for movement into and out of collapsed and extended positions, said legs supporting said seat portion when extended and forming therewith a generally plane structure when collapsed, a tablet arm assembly supported on said front and rear legs for movement relative thereto independently of said hinged movement of said legs and seat comprising, a 20 tablet arm, a supporting post fixed at one end to one of said front legs for swinging movement relative thereto along the adjacent side of said

5 chair, a first double-pivot means connecting said tablet arm to the free end of said supporting post for swinging movement relative thereto about either of a pair of generally normal axes on said post, a supporting bracket fixed to said chair rearwardly of the post connection therewith, and a second double pivot connection between said bracket and said tablet arm affording movement therebetween about generally normal axes, 10 one of said axes being common to both of said double-pivot connections, said second double-pivot connection including a bearing means affording sliding movement of said tablet arm along said common axis, whereby said tablet arm may 15 be laterally tilted from a horizontal to a vertical position and may also be rotated relative to said supporting post in a plane generally parallel to the path of movement of said post alongside said chair.
